UNITED STATES PATENT OFFICE.

HENRY J. HARTLEY, OF NEW YORK, N. Y.; EDWARD J. FOWLER, OF REDWOOD CITY,
AND DUDLEY BAIRD, OF BERKELEY, CALIFORNIA, ASSIGNEES TO NICHOLS COPPER
COMPANY, OF NEW YORK, N. Y., A CORPORATION OF NEW YORK.

ROASTING FURNACE.

Application filed July 21, 1926. Serial No. 123,864.

This invention relates to roasting furnaces and more particularly to multiple hearth rotating shaft furnace constructions.

In furnaces of this type difficulty has heretofore been experienced in providing a durable construction of commercial size and yet having its interior parts readily accessible and demountable for inspection, repair or replacement. The furnace construction embodying this invention may comprise a plurality of superposed hearths together with a surrounding furnace wall which are divided vertically of the furnace to form two separable furnace sections and if desired a carriage may be provided to facilitate the removal of one section, thus allowing the sections to be easily separated for inspection and cleaning. Also, if desired, the various hearths, supporting members and other parts within the furnace, may according to this invention be demountable for permitting examination, replacement and cleaning.

Various further specific objects, features and advantages will more clearly appear from the detailed description given below taken in connection with the accompanying drawings which form a part of this specification.

30 In the drawings, Fig. 1 represents a vertical sectional view taken near the vertical axis of a furnace construction embodying the invention;

35 Fig. 2 is a plan view showing the divided furnace wall construction embodying this invention, with the furnace sections in separated position;

Fig. 3 is an elevational view of the furnace parts shown in Fig. 2;

40 Fig. 4 is a horizontal sectional view of a furnace embodying the invention and showing a typical hearth construction and arrangement;

Fig. 5 is an elevational view showing in detail the manner of securing the hearth supporting arms to the furnace wall; and

Figs. 6 through 10 illustrate further details of a hearth construction embodying various features of the invention.

50 In the furnace as shown a plurality of vertically spaced or superposed and substantially circular hearths are designated by the numerals 11-16 inclusive. These hearths are

surrounded and supported from a substantially cylindrical masonry furnace wall 17. 55 The usual rotatable and internally cooled central shaft 18 extends vertically up through the furnace substantially along the central axis thereof and is provided in the usual manner with a series of rabble arms as 19 and 20 extending radially from the shaft into the space between succeeding hearths. Suitable rabble teeth 21 are provided along each of the rabble arms for advancing the material being treated successively over each of the hearths. A conduit is indicated at 22 for conveying the material to be treated into the furnace through a suitable feeding device as at 23. As shown in the drawing the top of the furnace may be surmounted by support members 24 and a cross member 25. The cross member 25 may serve to hold a central shaft 18 in place and also comprises a support for the feeding device 23. The material entering the feeding device first falls against a feed plate 26 from which it is fed to a delivery bed 27, as by means of a scraper 26^a attached to the shaft 18, where it may be given a preliminary heating. 70

The various features of the furnace construction embodying this invention have been found to be particularly adaptable for use in a furnace for treating silver slime and other semi-liquid ore products and the like. 85 The conduit 22 accordingly provides a suitable means for conveying this material to the furnace. It will be understood, however, that the invention is also adaptable for use with solid products, either finely or coarsely divided. For such ores the conduit 22 would, of course, be replaced by a suitable hopper of any well known construction. 90

If a semi-liquid ore is being treated, the feeding device 23 may be readily adjusted in height by an adjustable supporting bolt and nut at 28 so that the outlet of the feeding device will be only a short distance above the plate 26. The material which falls from the feed plate 26 to the delivery bed 27 is gradually advanced to a hopper 29 by the rabble arms as at 19 having teeth 21 directed at an angle to deflect the material outwardly from the center of the delivery bed of the hopper 29. The hopper 29 may form a part of an ore luted feeding 100 105

device comprising a shelf 30, and a scraper 30^a, which cooperate with the hopper in a manner similar to the operation of the feeding arrangement above described. A sufficient quantity of the semi-liquid ore rests upon the feeding plate to close off the feeding device at all times against the exit of furnace gases and still without interrupting the desired continuous inward flow of ore. The material being treated is scraped or allowed to flow from the shelf 30 and passes down through the furnace and over each of the successive superposed hearths, alternate hearths being provided respectively with central and peripheral discharge openings as at 31 and 32 so that the ore or other material is gradually advanced inwardly of one hearth toward the central opening and outwardly over the next hearth toward the peripheral opening or openings.

In the treatment of silver slime or other semi-liquid ore products the water content of the product will be gradually driven off on the upper hearths and as the material advances over the lower hearths it will be rapidly calcined or otherwise suitably acted upon under the temperature conditions and in the particular atmosphere present. In treating silver slime this material will be kept from forming into dried cakes because of the continuous rabbling by the rabble arms. The rabble arms will maintain the product in a more or less uniformly finely divided state throughout the operation, thus constantly exposing all particles of the product to substantially uniform temperature conditions and to uniform and rapid action by the gases present in the furnace. Accordingly, when the product reaches the lower hearth, it is generally finely divided and uniformly calcined or otherwise treated.

In order to render the interior parts of the furnace readily accessible for inspection, repair or replacement and for other purposes, it has been found desirable to divide the furnace vertically so as to form a stationary furnace section 33 (see Figs. 2 and 3), and a removable furnace section 34. This may be accomplished by constructing the cylindrical furnace wall portion in two parts, the line of division being substantially along the diameter of the furnace, the various hearths being similarly divided into two portions which are each supported respectively from the stationary and removable wall section. Each of the wall sections along the line of division may be provided with flanges as at 35 and 36, which fit together when the furnace sections are in operative position and may be secured in any desired manner as by bolts. The frame parts of the respective sections of the furnace may be further secured together as by bolts extending through apertures as at 37 and 38 (see Fig. 1), when the furnace sec-

tions are placed together in their closed operative position.

As indicated in Fig. 3, the stationary furnace section may be mounted upon suitable supports 39, whereas the removable section 70 may be provided with a carriage 40 arranged to engage rails 41. A central rotatable shaft carrying the rabble arms and its supporting structure may be preferably associated with the stationary furnace section and operated by a suitable source of power, such as the rotating shaft 42 which in turn is operated through suitable speed reducing gearing indicated at 43.

Each of the hearth areas may comprise a plurality of blocks or plates of heat resisting material as at 44, 45 and 46, preferably demountably arranged upon suitable supporting means. In the particular construction illustrated, this supporting means may take the form of radially extending arms as at 47 and 48, (see Fig. 1). As shown in Fig. 5, these arms may be fitted to the furnace wall with a mortise and tenon joint comprising a cavity 49 formed in the masonry of the wall and of such dimensions as to fit the end of the supporting arm. In the construction here shown the exterior of the furnace wall comprises a sheet metal plate 50 and the supporting arm may be suitably secured as by bolts 51 to this plate. It will be noted that the threaded portions of these bolts and also the nuts thereon are located exteriorly of the furnace where they are easily manipulated and are not subjected to the high temperatures prevailing within the furnace. The blocks or plates forming the hearth areas rest upon the supporting arms and are kept in the desired position thereon by suitable central ridges as at 52 formed upon the arms. Fig. 7 is a sectional view showing the cross-sectional form of a typical arm such as used between two hearth plates 44. The outside edges of the hearth plates may be additionally supported directly from the furnace wall in the manner shown in Fig. 6, which illustrates a corbeled wall portion engaging the rim of a hearth plate 44.

The hearth plates may be formed of any suitable material capable of resisting the high temperatures necessary with the particular process for which the furnace is to be used. Cast iron plates are satisfactory for certain installations, whereas in other processing requiring high temperature roasts, it is advisable to use tile plates. The supporting arms may be formed if necessary of high temperature alloys capable of withstanding the desired high temperatures.

The hearths are here illustrated as substantially horizontal although it will be appreciated that if desired, the supports and hearth plates here shown may be made interchangeable with other supports and hearth plates to provide hearths inclined either in-

wardly or outwardly of the furnace. Such interchangeable inclined hearths may be utilized to either promote or retard the flow of material through the furnace as desired.

5 The furnace may be therefore more or less universally used with different ores and materials and the process varied to suit either temporary or permanent requirements without the necessity of rebuilding or redesigning the entire structure.

When the furnace is used in the treatment of silver slime or other valuable ore products, the demountable features of this furnace are highly desirable, since they facilitate complete removal of the ore deposits for inventory purposes without possibility of waste. Hearth plates as shown may be interchanged with other hearth plates having ore openings of various other dimensions or arrangements as may be desired for various methods of operating the furnace.

It will be understood that the demountable hearths as above described may be used either with furnaces having solid continuous walls or with furnaces that are separable into sections as here shown. With the sectional construction, it is desirable to provide special means to insure proper engagement of the hearth plates at the line of division of the furnace sections. Fig. 9 is a sectional view at the line of division showing in detail the abutting edges of two hearth plates of suitable construction. The hearth plate 46 for example, may be provided with a depending lip or flange portion 53 having a beveled edge 54 for engaging and sliding under the lower edge of the hearth plate 45. When the two furnace sections are in closed or operating position, the hearth plates 45 and 46 will be in the relative positions shown in Fig. 9, thereby insuring a suitable joining of the hearth areas along the line of separation. In order that the hearth plates as at 45 and 46 at each side of the line of division will be supported in stable condition even when the furnace sections are separated, each of these plates may be made to extend over at least two of the radial supporting arms as 47 and 47' (see Figs. 4, 7 and 10).

50 If desired, the adjacent inner ends of each pair of supporting arms may be rigidly held in their proper spaced relation by stay members as at 55 through which a securing bolt 56 may extend. (See Fig. 8).

55 The usual practice as followed in the design of furnaces of this general type may be followed as to constructional details which are not specifically referred to herein.

60 While the invention has been described in detail with respect to certain particular preferred examples which give satisfactory results, it will be understood by those skilled in the art after understanding the invention, that various changes and modifications may

be made without departing from the spirit 65 and scope of the invention and it is intended, therefore, in the appended claims to cover all such changes and modifications.

What is claimed as new and upon which it is desired to secure Letters Patent of the 70 United States is:

1. A multiple hearth rotary shaft furnace construction comprising a plurality of superposed hearths surrounded by a furnace wall, said hearths and wall being divided 75 vertically of the furnace to form a stationary furnace section and a removable furnace section, the hearth areas of each section each being made up of a plurality of blocks or plates of heat resisting material supported from 80 the wall sections.

2. A multiple hearth rotary shaft furnace for commercially treating large quantities of ore or the like by a continuous roasting process, comprising a plurality of superposed hearths surrounded by a furnace wall, said hearths and wall being divided vertically of the furnace to form a stationary furnace section and a removable furnace section, a carriage for said removable section 90 whereby the sections may be readily separated for inspection and cleaning, the hearth areas of each section each being made up of a plurality of blocks or plates of heat resisting material supported from the wall 95 sections.

3. A multiple hearth rotary shaft furnace construction having a plurality of vertically spaced substantially circular hearths surrounded by a substantially cylindrical furnace wall, said hearths and wall being divided substantially along the vertical axis of the furnace to form two separable furnace sections, whereby the interior may be made accessible for inspection or cleaning, hearth supporting means extending from the walls of each section, and the hearth areas of each section each comprising a plurality of blocks or plates of heat resisting material arranged upon said supporting means.

4. A multiple hearth rotary shaft furnace construction comprising a plurality of superposed hearths surrounded by a substantially cylindrical furnace wall, each hearth being formed of demountable sectors of heat resisting material supported upon demountable arms extending from said wall.

5. A multiple hearth rotary shaft furnace construction comprising a plurality of superposed hearths surrounded by a substantially cylindrical furnace wall, each hearth being formed of demountable sectors of heat resisting material supported by said wall.

6. A multiple hearth furnace construction comprising a plurality of superposed hearths surrounded by a furnace wall, each hearth being divided into at least two sections demountably secured to said wall.

7. A multiple hearth rotary shaft furnace construction comprising a plurality of superposed hearths surrounded by a substantially cylindrical furnace wall, said hearths and wall being divided vertically of the furnace to form a stationary furnace section and a removable furnace section, the hearth portions of each section being demountable in respect to the wall portions of their respective sections. 65
8. A multiple hearth rotary shaft furnace construction comprising a plurality of superposed hearths surrounded by a substantially cylindrical furnace wall, said hearths and wall being divided vertically of the furnace to form a stationary furnace section and a removable furnace section, the wall being also formed with a plurality of apertures at each hearth, and hearth supporting arms demountably secured in said apertures. 70
9. A multiple hearth furnace construction comprising a plurality of superposed hearths surrounded by a furnace wall, said wall being formed with apertures adjacent each hearth, hearth supporting arms demountably secured in said apertures, and demountable hearth plates of heat resisting material resting upon said arms. 75
10. A multiple hearth furnace construction comprising a plurality of superposed hearths surrounded by a furnace wall, said wall being formed with apertures adjacent each hearth, hearth supporting arms demountably secured in said apertures, demountable hearth plates of heat resisting material resting upon said arms, and means accessible for release at the exterior of the furnace for securing said arms in position in the furnace wall. 80
11. A multiple hearth furnace construction comprising a plurality of superposed hearths surrounded by a furnace wall, said hearths being made up of demountable plates of heat resisting material, and said wall being corbeled at each hearth to provide a rim support for said plates. 85
12. A multiple hearth furnace construction comprising a plurality of superposed hearths surrounded by a furnace wall, said hearths being made up of demountable sector shape plates of heat resisting material, and supporting arms of heat resisting material extending substantially radially inwardly from said wall beneath adjacent edges of said plates. 90
13. A multiple hearth furnace construction comprising a plurality of superposed hearths surrounded by a furnace wall, said hearths being made up of demountable sector shaped plates of heat resisting material, supporting arms of heat resisting material extending substantially radially inwardly from said wall beneath adjacent edges of said plates, and means for securing to- 95
- gether at their inner ends adjacent pairs of said arms. 100
14. A multiple hearth furnace construction comprising a plurality of superposed hearths surrounded by a furnace wall, said hearths being made up of demountable plates of heat resisting material and supporting arms demountably secured to said wall and extending beneath and between adjacent edges of said plates. 105
15. A multiple hearth furnace construction comprising a plurality of superposed hearths surrounded by a furnace wall, said hearths and wall being divided for forming two separable furnace sections, the hearths being made up of demountable plates of heat resisting material, the hearth plates of one furnace section being formed with depending flanged edges for underlying the corresponding hearth plate edges of the other furnace section along the line of division of the furnace. 110
16. A multiple hearth furnace construction comprising a plurality of superposed hearths surrounded by a furnace wall, said hearths and wall being divided for forming two separable furnace sections, the hearths being made up of plates of heat resisting material, the hearth plates of one furnace section being formed with means for overlapping and retaining in horizontal alignment therewith the abutting edges of the hearth plates of the other furnace section. 115
17. A multiple hearth rotating shaft furnace for commercially treating large quantities of ore or the like by a continuous roasting process, comprising a plurality of superposed hearths surrounded by a furnace wall, said hearths and wall being divided vertically of the furnace and forming relatively movable sections, a carriage for at least one of said sections whereby the sections may be readily separated for inspection and cleaning, the hearth areas of each section comprising blocks or plates of heat resisting material supported from the wall sections. 120
18. A multiple hearth rotating shaft furnace for commercially treating large quantities of ore or the like, comprising a plurality of superposed hearths surrounded by a furnace wall, said hearths and wall being divided substantially along the vertical axis of the furnace into two relatively movable sections, the hearth areas of each section comprising demountable blocks or plates of heat resisting material supported from the wall sections and accessible for cleaning or replacement upon separation of the two furnace sections. 125
